[57] CLAIM

The ornamental design for a data input machine for a
television monitor, as shown and described.

DESCRIPTION

FIG. 1 is an inverted rear elevational view of a data
input machine for a television monitor showing our new
design;

FIG. 2 is a left-side elevational view thereof;

FIG. 3 is a top plan view thereof;

FIG. 4 is a right-side elevational view thereof;

FIG. 5 is a bottom plan view thereof;

FIG. 6 is a front elevational view thereof;

FIG. 7 is a top front and right side perspective view
thereof with pen being shown in broken lines for illus-
trative purposes only and forms no part of the claimed
design; and,

FIG. 8 is a top, front and right-side perspective view
thereof, shown with the pen removed.

FIG. 1

FIG. 2

FIG. 3

FIG. 6

FIG. 5

FIG. 4

FIG. 7
